UNITED STATES PATENT OFFICE.

GROVER H. JONES, OF LOS ANGELES, CALIFORNIA.

COUNTER.

1,243,610.

Specification of Letters Patent. Patented Oct. 16, 1917.

Application filed March 6, 1917. Serial No. 152,723.

To all whom it may concern:

Be it known that I, GROVER H. JONES, a citizen of the United States, residing at Los Angeles, in the county of Los Angeles and 5 State of California, have invented new and useful Improvements in Counters, of which the following is a specification.

This invention relates to a registering device and particularly pertains to a counter.

10 It is the principal object of this invention to count and register the number of times a machine or apparatus has been actuated by the use of a single and effective counting device.

15 This device is particularly adapted for use in street sewer systems to register the number of times the flush basins have been emptied in a given period of time. Due to the simplicity of the counter, its use in such 20 places will eliminate the services of numerous inspectors and permit the sewer systems to be maintained in a proper sanitary condition at slight expense.

Another object of this invention is to provide 25 a counter which possesses no parts liable to become broken or inoperative from wear.

It is a further object of this invention to provide a counter which is formed of few parts, inexpensive in construction and easily 30 assembled.

Other objects will appear hereinafter.

The invention is illustrated, by way of example, in the accompanying drawings in which:

35 Figure 1 is a view in vertical section and elevation illustrating the counter as applied to the flush basin of a sewer system.

Fig. 2 is a view in plan illustrating the counter in detail and particularly disclosing 40 the sinuous course of travel of the counting element.

Fig. 3 is a view in transverse section as seen on the line 3-3 of Fig. 2 disclosing the depressions in the floor of the counting 45 table along which the counting element moves.

Fig. 4 is a view in plan illustrating the counter as mounted for operation upon its bearings.

50 Referring more particularly to the drawing, 10 indicates a flush tank which is connected with sewer pipes 11 and 12. The pipe 12 is here shown as formed with a trap 13 which drains the tank. The pipe 11 55 enters the tank from the opposite side and

near the top. Mounted upon this pipe is a pair of clamping brackets 14 and 15. These brackets are detachably secured around the pipe and are fitted with upwardly extending bearings 16 and 17. These bearings provide a pivotal mounting for a counter 18. While I have described the counter as mounted for use in connection with a sewer flush tank, it is to be understood that this combination is not an essential one and that 60 the counter may be used in connection with any apparatus or mechanism with which it will satisfactorily operate.

The counter, as here shown, is substantially square and is formed with a body 70 plate 19 having a flange 20 extending therearound. This flange extends upwardly from the body plate and serves as a mounting for a glass-cover 20'. Mounted at opposite sides of said body plate and in alinement with 75 each other are trunnions 21 and 22. These trunnions are positioned a distance off center from the body plate and insure that the weight of the eccentrically hung portion will co-act with a float member 23 to operate 80 the device. This float is suspended by a chain or cable 24 from an eye 25 formed at the end of the counter. In this manner the emptying of the tank 10 will relieve the float and cause the counter to swing upon 85 its trunnions in an oscillating movement. The counter is located so that it may be read by removing a manhole cover.

The oscillating movement of the counter plate is provided to propel a counting element 90 26. This element is here shown as a small ball which is adapted to move along a sinuous path of travel as the counter is oscillated. This movement is produced by the peculiar contour of the counter floor, 95 which is here shown as having a series of parallel grooves 27. These grooves are separated by ridges which are serrated, as particularly disclosed in Fig. 2 of the drawings. The floor of the grooves between the 100 serrations is formed with depressions 28. These depressions are so disposed in relation to each other as to cause the counting element to pursue a zig-zag course of travel back and forth along the groove and from 105 one serration to the other as the counter is successively oscillated. The down-stroke of one oscillation will cause the element to roll across and to register with the serration of one ridge and the upstroke of the same 110

oscillation will cause it to roll across diagonally to a serration in advance of the preceding one. It will be understood that the serrations forming the side walls of the 5 grooves are staggered in relation to each other so that the up and down stroke of the counter will cause the counting element to advance one serration along each side of the groove. These progressive steps in the 10 movement of the counting element are tabulated by means of graduations formed upon the surface of the glass cover 20' and in this manner the exact number of oscillations may be accurately registered. When the 15 counter is mounted, as disclosed in Fig. 1, the counting element is initially placed in the position shown in Fig. 2 of the drawings. When the tank is emptied, the float 23 will be relieved of the support of the 20 water in the tank and the counter will be swung upon its trunnions. As the tank again fills, the weight of the over-hanging portion of the counter will cause it to swing in the opposite direction. This will allow 25 the counting element to move across and advance along the groove 27. As the counter is successively operated, the element will finally reach a communicating passage-way 29 from which it will pass into a second 30 groove and along which it will continue. After the counting element has traversed the entire course across the floor of the plate, it will return to its initial position along a passage-way 30.

35 It will thus be seen that the counting device here described is decidedly simple in its construction and operation and that it will accurately register the number of times it is

oscillated regardless of the mechanism upon which it is mounted.

While I have shown the preferred construction of my counter as now known to me, it will be understood that various changes in the combination, construction and arrangement of parts may be made by those 45 skilled in the art without departing from the spirit of my invention.

I claim:

1. A counter comprising a pair of horizontally aligned bearings, a plate, trunnions 50 extending from the plate into the bearings and permitting oscillation of the plate, the plate being overbalanced one way, means for overbalancing the plate the other way, means forming a zig-zag path upon the 55 plate, a ball traveling in the path step by step, means directing the ball forwardly at each step and preventing a backward step, a transparent cover for the plate, and graduations upon the cover.

2. A counter comprising a plate pivotally mounted in a horizontal plane longitudinally and to oscillate transversely, the plate being overbalanced one way, means for overbalancing the plate the other way, means 65 forming a zig-zag path upon the plate with a depression at each turn in the path, a ball traveling in the path from depression to depression at each oscillation of the plate, means directing the ball forwardly at each 70 step and preventing a backward step, and graduations for indicating the number of steps.

In testimony whereof I have signed my name to this specification.

GROVER H. JONES.
